UNITED STATES PATENT OFFICE.

LYNN GRAY, OF WAUPUN, WISCONSIN, ASSIGNOR TO PARAMOUNT TEXTILE MACHINERY CO., OF CHICAGO, ILLINOIS, A CORPORATION OF ILLINOIS.

HOSIERY-FINISHING APPARATUS.

Original application filed March 24, 1921, Serial No. 455,088, now Patent No. 1,583,590, dated May 4, 1926.
Divided and this application filed April 8, 1926. Serial No. 100,601.

This invention relates, primarily, to hosiery finishing apparatus; it has reference, more especially, to structures for drying and shaping so-called "full-fashioned" and "mock-seam" hosiery; and the subject-matter thereof is completely disclosed in my parent application Serial No. 455,088, filed March 24, 1921, entitled "Hosiery drying and shaping forms," and patented May 4, 1926, as No. 1,583,590, and, consequently, the present case is a division thereof.

As distinguished from so-called "seamless" hosiery, "full-fashioned" hosiery is of a type that is knit in sheet form and, then, has its two longitudinal edges sewed together, there being presented, thus, a seam extending from the toe to the top of the stocking.

"Mock-seam" hosiery is knit in tubular form and is, in fact, seamless; but, to meet a public demand, a longitudinal seam is simulated in the fabric, so that the article resembles full-fashioned hosiery.

When the goods have been dyed or bleached, they are usually maintained in a damp condition for a finishing operation. This involves placing them on forming instrumentalities, usually called drying boards or forms. The operation is known in the industry as "boarding" or "finishing." The product is thereby dried, shaped and creased front and rear.

In the "boarding" of both full-fashioned and mock-seam hosiery, the present-day practice with most manufacturers is to lay the seam—whether it be the real seam in full-fashioned hosiery or the simulated seam in mock-seam hosiery—to one side of the crease or longitudinal line therein extending at least from the heel to the top of the stocking. This practice results in the production of what are called "rights" and "lefts," these designations arising from the fact that the seam, during the boarding, is disposed to the right or to the left of the rear crease. The "rights" and "lefts" are paired, as such. The structure of my present invention is characterized not only by having its front and rear portions provided with crease-producing edges but, also, by having, at opposite sides of the rear crease-producing edge thereof, seam-seating incuts or guiding surfaces with walls which are more or less angularly disposed to each other, and which form a seam-seating cavity.

Each incut includes a seam-engaging surface, and two proximate surfaces terminate in and constitute the rear crease-producing edge of the form. That is to say, the rear portion of the form, from the toe to the base thereof—or from the heel to the base, in some instances—is provided with a pair of incuts, these being separated by a crease-producing edge, this latter involving the extremities of the proximate seam-engaging walls of the incuts, whereby the seam in the hosiery, when boarded on the form, will be disposed either to the right or the left side of the crease therein formed by the crease-producing edge.

In my aforementioned parent application, Serial No. 455,088, one of the two types of forms disclosed and claimed therein has but one seam-seating incut, so that, to "board" hosiery as "rights" and "lefts," two forms are required—a pair, in other words—one with the incut at one side of the crease-producing edge and the other with the incut at the opposite side thereof. In other words, to board a pair of stockings, a pair of these forms is utilized, each having its incut oppositely disposed to that in the other. With the structure of the present form, however, boarding of both "rights" and "lefts" on the one form is rendered possible and, as a consequence, the number of forms required in a plant is reduced, approximately, one-half. Manifestly, where in a hosiery-manufacturing mill a large number of these forms are employed for finishing hosiery, the reduction of the hosiery-finishing devices by one-half, say, involves a tremendous saving, not only in the expense of the equipment itself but, also, in floor space, etc.

It will be understood that where hosiery having either an actual seam or the aforementioned mock-seam is boarded on a form of the character described, that seam is initially positioned by the operator in one or the other of the incuts, and it of course remains therein during the drying operation. When the stocking is stripped from the form, the seam will lie in a straight longitudinal line and occupy a position either to the right or to the left of the crease in the stocking, according to which incut it had occupied in the form. By reason of the rapid evaporation of the moisture from the fabric of the stocking while on the form during the drying and

finishing operation, the seam thereof, as well as the fabric, is "set" so that, in the finished product, the seam will remain in a fixed relation to the crease, according to whether it is 5 on the right or the left side thereof.

In order that my invention may more readily be comprehended, I have herein illustrated one embodiment thereof; it being understood, however, that this is merely illustrative, that my inventive-concept is susceptible of other embodiments and utilizations, and that the particular embodiment shown is capable of a wide range of variation and modification without departing from the essence of the invention or sacrificing any of 10 the underlying principles or salient features thereof.

In these drawings:

Figure 1 is a view in perspective of an interiorly-heated hosiery drying and shaping form—of the general character shown in 20 United States Patent No. 1,204,945, dated November 14, 1916, to George Collis, on the "art of finishing and shaping hosiery"—and having a full-fashioned stocking superposed thereon, a portion of the latter being cut away to disclose, first, the seam-receiving incut in the form and, also, the relation thereto of the seam in the article;

Figure 2 is a somewhat enlarged view in 30 transverse section, on the line 2—2, Figure 1; and

Figure 3 is a fragmentary view, also in transverse section but on a very much larger 35 scale, showing the portion of the form which is provided with the pair of seam-seating incuts.

Referring to these drawings, the reference-character 1 designates a stocking of the so-called "full-fashioned" type having a seam 2 40 at the back and extending from the toe of the stocking to the top thereof. It will be understood that where the stocking is of the "mock-seam" type, the simulated seam usually extends only from the heel to the top of the stocking; but the presence of the mock-seam requires the finishing operation to be the seam. For the purpose of this disclosure, therefore, it will be sufficient to assume that 45 the stocking, as illustrated, is of either the full-fashioned or mock-seam type. So far as the functioning of my invention is concerned, it is substantially the same as applied to both types.

The stocking, in this instance, is shown as 55 superposed upon a form 3—of the aforementioned patented type—adapted simultaneously to dry, shape and crease it. The form is, in this instance, hollow (as at 4) to contain 60 a thermal fluid for heating it interiorly. It is to be understood, however, that it may be solid and may be heated in any required manner, as by electricity, etc.

Preferably and as shown, the form 3 has 65 arc-shaped or bulged sides 5, these being

shaped to conform to the shape of a stocking so as to effect a shaping thereof, the sides thereof terminating in crease-producing edges 6 and 7. These sides and edges function to effect, simultaneously, a shaping, creasing and finishing of the hosiery while it is being dried on the form.

Disposed at opposite sides of the rear crease-producing edge 7 is a pair of incuts 8 which, in a form adapted for boarding full-fashioned hosiery, extend from the toe-end 75 9 of the form to the base 10 thereof. Where the form is adapted for boarding mock-seam hosiery, the groove may extend only from the heel 11 to the base 10.

In the embodiment shown in Figs. 1 to 3, each incut is of substantially L-shape in cross-section and, thus, includes a seam-engaging surface 12, an angular surface 13, and a corner 14, the two corners being connected by an 85 edge-section 15. The juncture of the two surfaces 12 and 13 presents a seam-seating section of the incut.

By reason of the disposition of the two incuts in juxtaposition, the two seam-engaging surfaces 12 of the pair are in substantial parallelism and, thus, merge into the edge 7. Thus, it is apparent that the crease-producing edge includes elements of the two incuts: The latter are, in other words, definitely related, 95 one to the other, so that part of each merges into the two and form a crease-producing surface, namely, the edge 7. In other words, the termini of the outstanding sections of the incuts form the crease-producing edge. The 100 surface 12, in this instance, occupies a plane at one side of a line cutting through the opposite crease-producing edge 6. Hence, the two surfaces 12 are on opposite sides of that line, while the surfaces 13 are angularly disposed 105 in relation thereto. In operation, when a seam 2 occupies and is seated in one of the incuts—the right one, say—the section of the fabric on the opposite side of the seam bridges the left incut, while the edge-section 15 is 110 forming the crease in the goods. It is to be understood that, in making the incuts, the corners 14 are not purposely produced; in fact, they are really existent only in a more or less magnified sense. The aim is, in making the crease-producing edge, to form it by merging the surfaces 12 into each other without, of course, making a cutting edge. From this, it will be manifest that the juxtaposed 115 relation of the incuts results in the two incuts forming, together, an entity—the crease-producing edge—which determines the position of the crease in the goods while the surface 12 determines the position and relation of the seam to the crease and the distance therefrom it shall occupy.

It will be observed that the edge 7 is directly opposite to and in line with the crease-producing edge 6. Thus, the form has a pair of oppositely-disposed crease-producing 125 130

edges. It will also be observed that the surfaces of the incuts which merge into and form the rear edge constitute a crease-producing instrumentality 7 for creasing the rear portion of the stocking simultaneously with the production of a crease by the front edge 6 in the front of the stocking.

From the foregoing, it will be perceived that I have devised a unique hosiery-boarding form peculiarly adapted for the finishing not only of full-fashioned and mock-seam hosiery but one so constituted that a single device is presented for boarding either "rights" or "lefts", as may be required.

15 It will be understood, of course, that the presence of the incuts in the form does not prevent satisfactory boarding of seamless hosiery of the type which is not provided with the aforementioned mock-seam.

20 It is now generally known that, as hosiery is pulled onto the heated forms in a comparatively damp condition, the moisture in the fabric will be quickly evaporated and the fabric in consequence is "set" or fixed. In the 25 initial boarding operation, the hosiery, when placed on the forms, is stretched to the dimensions approximately of the ultimate product and then, before becoming set, is manipulated to position the seam in one or the other of the 30 incuts in the form. The evaporation of moisture from the fabric not only produces the aforementioned "setting" or fixing thereof, but, also (and simultaneously) the making and fixing of the creases in the front and rear 35 portions and of the seam, itself, so that the product (including the seam) is thereby given a finished appearance and made ready for the market without subsequent finishing treatment.

40 What I claim is:

1. A drying and shaping structure for treating hosiery including a form provided with oppositely-disposed crease-producing edges and with a pair of incuts at opposite sides of and adjacent one of the edges, each incut including a seam-engaging surface whereby seamed hosiery can be boarded, either as a "left" or as a "right" on the structure, the two engaging surfaces terminating in and forming one of the crease-producing edges whereby a crease may be selectively produced in the hosiery

with the seam therein disposed at one or the other side thereof.

2. A hosiery drying and shaping structure provided with oppositely-disposed crease-producing edges and with a pair of incuts at opposite sides of one of the crease-producing edges, each incut comprising a seam-seating section whereby seamed hosiery can be boarded, either as a "left" or as a "right" on the structure, the outstanding walls or surfaces of the two incuts terminating in and forming one of said crease-producing edges whereby a crease may be selectively produced in the hosiery with the seam therein disposed at one or the other side thereof.

3. A hosiery drying and shaping structure having oppositely-disposed crease-producing edges, and a pair of incuts, one at each side of one of the crease-producing edges, each incut comprising a seam-seating section, the outstanding walls of which merge into and form one of said crease-producing edges, the section of the structure involving the incuts being formed of a web of material relatively thinner than the body-portion of the structure and presenting two walls at opposite sides of a median line extending transversely through the structure, these walls being joined by a connecting wall or surface constituting said crease-producing edge whereby a crease may be selectively produced in the hosiery with the seam therein disposed at one or the other side thereof.

4. A drying and shaping structure for treating hosiery including a form provided with oppositely-disposed crease-producing edges and with a pair of approximately L-shaped incuts at opposite sides of and adjacent one of the crease-producing edges, each incut comprising angularly-disposed surfaces including a seam-engaging surface whereby seamed hosiery can be boarded, either as a "left" or as a "right" on the structure, the two engaging surfaces terminating in and forming one of said crease-producing edges, whereby a seam of the stocking may at the will of the operator be positioned at either side of the crease effected by the proximate crease-producing edge.

In testimony whereof I affix my signature.
LYNN GRAY.
